2 Claims. (Cl. 234—70)

1

My invention relates in general to picture transmission systems and more particularly concerns a novel means for recording facsimile images upon a dry conductive record sheet.

In facsimile transmission systems, a transmitting-scanning member is operative to generate electrical currents which fluctuate in accordance with the lights and shades of elemental areas of an image to be transmitted. These currents are amplified and are transmitted by wire or radio to a remotely disposed recording unit. The recording process generally comprises the operation of a stylus across a record sheet in a manner which duplicates the motion of the scanning member at the transmitter.

In one form of facsimile recording system, the recording sheet is paper or similar material rendered conductive by impregnation with a suitable metallic element such as finely divided carbon or finely divided aluminum.

One surface of this conductive sheet is chemically sensitized by a material such as titanium oxide which discolors upon the passage of an electrical current therethrough. The recording sheet is mounted upon a conductive platen and is traversed by a conductive stylus in contact therewith.

The incoming facsimile signals are impressed between the surfaces of the conductive sheet by applying these signals to the conductive stylus and to the conductive platen and accordingly the discolorations of the recording sheet will vary substantially as the corresponding light shades of the image at the transmitter.

The method of recording upon dry conductive paper offers many advantages notably the production of an instantaneous recording which requires no further chemical processing to create the desired image. However, the utilization of dry recording has been accompanied by various disadvantages which have often marred the fidelity of the reproduction to a point where the image was unrecognizable.

The disadvantages resulting from the use of dry recording paper in conjunction with a recording stylus have been in part a result of conductive stylus utilized to traverse the recording sheet. Generally, the stylus utilized assumed the form of a needlelike metallic member biased against the conductive paper. The area of contact between the end of the stylus and the surface of the recording sheet was necessarily of the order of the area covered by a scanning member at the transmitter.

Since the transmitting scanning member nor-

2

mally comprised a light beam focussed to a spot upon the surface of the image, this scanning spot was of relatively small diameter and normally less than $1/100$ of an inch. Thus the recording stylus was correspondingly of the order of $1/100$ of an inch in diameter so that the width of a scanning line drawn by the recording stylus was substantially equal to the width of the line scanned at the transmitter.

10 The utilization of fine diameter recording stylus was impossible with dry recording paper of the type described, since stylus having relatively sharp recording points would tend to cut into the recording sheet. Furthermore, the consideration 15 of the mechanical strength of the stylus was important in determining the minimum diameter which could possibly be utilized.

Amongst the foremost disadvantages of a pointed recording stylus for traversing a conductive sheet was the accumulation of gummy conductive substance thereupon due to the aforementioned cutting effect which the stylus exercised upon the recording sheet.

Since the recording sheet is essentially conductive throughout, the material which would tend to accumulate upon the point of the recording stylus was correspondingly conductive and thus the effective conductive area in contact with the recording sheet would increase greatly as the recording progressed.

Consequently the final image would be blurred as the width of the recording trace increased due to the accumulation of conductive matter upon the stylus and the resulting pictures were at 35 times distorted beyond recognition.

In order to preclude the deposition of conductive material upon the stylus point which would result in an overlap of the recording traces, a wafer stylus was devised.

40 This recording stylus comprised a fine disk rotatably supported upon the scanning arm and having associated cleaning apparatus for removing any material which would tend to deposit.

The stylus would traverse the sheet in a rolling contacting manner, and thus by the application of a wiper to the edge of the stylus, it was possible to remove accumulated material.

A disadvantage, however, of the rolling contacting type of stylus is evident when an attempt 50 is made to record the finest details of an image. Thus, although the disk stylus could be made as thin as practical to obtain a scanning line of extremely fine width, the stylus still had to be of appreciable diameter in order to provide for the 55 rotatable support and the like.

Since dry conductive paper or similar material is relatively soft, the rotatable stylus would tend to cut into the paper and thus electrical contact would be made over a surface which was substantially rectangular. In other words, the stylus would contact the paper over a width equal to the width of the stylus and over a length in the direction of the scanning movement which was a function of the depth to which the stylus would penetrate.

Thus the resolution of fine detail by means of a disk stylus has been found impossible.

Summarizing the above, therefore, it may be seen that prior recording styli of the conductive type for operating upon instantaneously chemically treated recording paper presented two salient difficulties namely the tendency to cut into the paper and the tendency to smudge or blur the image as a result of the accumulation of the conductive material thereupon.

The present invention contemplates a needle like recording stylus which overcomes the aforementioned disadvantages of recording styli hereinabove enumerated. The novel recording stylus of my invention comprises essentially a needle like structure embedded in an insulating compound which serves as a support therefor.

The surface area of contact between the novel conductive stylus and the recording sheet may be made as small as is consistent with the detail which it is desired to record faithfully, while the accumulation of conductive material about the recording edge thereof is impossible. Furthermore the problems heretofore experienced insofar as mechanical support for the stylus was concerned, have been completely overcome by the present stylus arrangement.

The needle like stylus is embedded in an insulating compound of durable characteristics and an exposed edge thereof is adjusted to be flush or coextensive with the surface of the insulating material. The surface of the insulating material containing the exposed edge of the recording stylus is preferably spherical or the like in form and of a relatively large radius of curvature as compared with the diameter of the stylus.

The surface of the insulating material and the exposed edge of the stylus are highly polished to present a uniform smooth contacting surface. The entire assembly of stylus and insulating embedment therefor, is then suitably positioned within a scanning apparatus at the recorder and is biased to surface engagement with the recording sheet.

It is obvious that during the motion of this recording stylus across the conductive sheet that it will be impossible for the relatively smooth contacting surface to cut or otherwise mar the surface of the recording sheet. Furthermore the relatively broad surface area presented by the entire stylus assembly will serve during the recording process to smooth the conductive nap of the recording sheet which would normally tend to be dislodged and accumulate upon the stylus.

I have discovered that I may fabricate the stylus of as fine a diameter wire as possible and provide sufficient mechanical support and bracing solely by the insulating embedment.

It is therefore an object of my invention to provide a novel recording stylus.

Another object of my invention is to provide a facsimile recording stylus of extremely fine diameter in an insulating embedment.

Still another object of my invention is to provide a recording stylus which will preclude the

accumulation of conductive material thereupon.

A further object of my invention is to provide for a recording stylus of extremely small recording area which will not cut or otherwise mar the surface of the recording sheet.

A still further object of my invention is to provide for a recording stylus having an exposed contacting surface of relatively small area and an insulating embedment providing mechanical strength therefor.

These and other objects of my invention will now be apparent from the following detailed specification taken in connection with the accompanying drawings, in which:

Figure 1 is a diagrammatic representation of a facsimile recorder.

Figure 2 is a schematic representation of the principles of my novel recording stylus, and

Figure 3 is a cross-sectional view of the recording elements of a facsimile scanner and illustrates my novel recording stylus in connection therewith.

A conventional type of facsimile recorder is illustrated in Figure 1 and is adapted for the novel type of stylus which I have devised.

As previously mentioned, a transmitting unit having a light beam stylus and associated photoelectric cell may generate electrical signals fluctuating in accordance with the lights and shades of pictures to be transmitted. These signals may be caused to modulate a radio frequency carrier and be transmitted thereby to a receiver such as illustrated in Figure 1.

At the receiver, an antenna 21 serves to intercept the radio signals and impress them through radio frequency transformer 22 upon a diagrammatically illustrated radio frequency amplifier 23. The output of this amplifier 23 is then detected by a detector 24 of conventional circuit design and the detected low frequency signals are then impressed upon a rectifier 25.

Obviously if a telephone transmission line is utilized instead of radio transmission system, the radio frequency amplifiers and detectors may be dispensed with.

The actual electromechanical recorder illustrated in this embodiment is of the rotatable drum type. As illustrated, a source of mechanical energy such as electric motor 26 energized from a power line through the leads 27 drives the drum 31 through a speed reducer 32.

The motor also drives worm 33 and thus associated worm gear 34 which imparts a rotary motion to the feed screw 35, suitably journaled as schematically illustrated. The feed screw 35 drives, by means of half nut 36 which is in engagement therewith, the recording stylus assembly which will hereinafter be described in further detail. The pitch of the feed screw is predetermined so that the recording stylus assembly 37 advances approximately $1/100$ of an inch during each revolution of the drum 31.

If, however, it is desired to place the scanning lines closer together, the pitch of the feed screw 35 may be decreased accordingly. The drum 31 is conductive and supports a record sheet 41 thereupon. The record sheet may of course be mounted in any suitable manner and as indicated, the record sheet is arranged to have an overlap at 42 and is maintained in fixed relation with the drum 31 by means of a pair of garter springs 43 and 44 which encircle the cylindrical drum 31 and support the paper thereupon.

The drum is rotated in the direction indicated by arrow head 45 in order to preclude interference

between the overlap 42 of the recording sheet and the edge of the recording stylus as will be more particularly described in later paragraphs.

The conductive drum 31 is supported in appropriate bearings and one terminal of the rectifier output is connected thereto through brush 46 which bears against the supporting shaft thereof. The other terminal of the rectifier output is coupled to the recording stylus assembly 37 as indicated and thus the rectified signals are impressed against the surface of the recording sheet 41.

The recording sheet may in one form comprise a conductive paper base formed by mixing a suitable quantity of wood pulp and a powdered metallic element such as carbon. The finished carbon paper which is black is then suitably coated with a chemical sensitizing layer such as titanium oxide which is white.

The recording sheet is mounted upon the conductive drum 31 so that the exposed surface of the conductive carbon paper is adjacent the metallic drum 31 whereas the titanium oxide coated surface is exposed to the action of the recording stylus supported upon the stylus assembly 37.

When an electric current is passed through a recording sheet of this type, the titanium oxide is discolored or broken down so that the carbon sheet shows through as black. The degree of discoloration will depend upon the amplitude of the current passing therethrough and thus the image produced is a replica of the image at the transmitter when the rectified facsimile currents are impressed between the drum and the stylus as illustrated in Figure 1.

Since the drum rotates while the stylus progresses parallel to the axis thereof, the scanning line is a helical trace. At the transmitter a similar scanning apparatus may be utilized except that a light beam and associated photoelectric cell may be substituted for the conductive stylus assembly 37 as is well known in the facsimile transmissions art.

As previously described, former facsimile apparatus utilized a recording stylus mounted upon support 37 which constituted a needle or a disk for the application of electrical potential to a localized area of the recording sheet.

The general principle of my novel recording stylus is illustrated in the fragmentary view of a recording machine Fig. 2. As illustrated, the record sheet 41 comprising the chemically sensitized sheet disclosed above is carried in close contact with the conductive drum 31.

The recording stylus comprises a conductive needle 51 in an insulating embedment 52 rigidly affixed thereto. The stylus 51 has an exposed surface 53 which contacts the sensitized surface of the recording sheet 41. The insulating embedment 52 which surrounds the stylus 51 provides the necessary mechanical support therefor and in addition provides the end curved surface 54 which is coextensive with the exposed surface 53 of the needle 51.

The assembly of the stylus 51 and the insulating material 52 is polished as a unitary structure so that the surfaces 53 and 54 are flush and are extremely smooth. The needle 51 is normal to the surface 54 at the point where the edge 53 is exposed.

The radius of curvature of the exposed surface 54 is relatively large and thus the stylus assembly illustrated in Figure 2 presents a smooth curved surface to the sensitized surface of the record sheet 41.

The particular form of the insulating embedment 52 for the needle stylus 51 is immaterial in that the contacting or printing surface thereof need only be of a particular form.

Obviously, the metallic element 51 of the stylus assembly illustrated in Figure 2 may be of as small a diameter as desired and accordingly, the trace of the stylus needle upon the recording sheet due to the passage of an electric current is similarly narrow. The actual diameter will be determined by the details it is desired to record and the diameters of the light spot which is focused upon the image at the transmitter.

The insulating embedment 52 may be of various materials including the various insulating plastics such as Bakelite, Lucite, and the like or the various ceramics, porcelain, plaster of Paris or glass.

The actual method of forming the stylus will be described in particular in connection with Figure 3. However, it is pointed out that the actual materials utilized for the metallic element 51 and the insulator 52 constitute no limitation since these may be varied to give the characteristic required for the particular recording sheet used.

The drum 31 illustrated in Figure 2 may be energized as illustrated in Figure 1 and the metallic element 51 of the schematically illustrated stylus assembly 51-52 may be energized through a lead wire 55 suitably soldered at 56 thereto.

A stylus fabricated as that schematically illustrated in Figure 2 has several improved novel characteristics which eliminate various problems heretofore encountered in instantaneous recording upon conductive paper. Thus it may be seen that the diameter of the metallic element 51 and thus the metallic area 53 contacting the sensitized surface of the record sheet 41 may be comparatively small without in any way impairing the mechanical characteristics thereof.

Furthermore, it may be seen that the relatively broad contacting surface which is a result of the combined coextensive surfaces 53 and 54 cannot in any way mechanically mar the surface of the record sheet 41. Thus the smooth finish of the surfaces 53 and 54 and the gradual curvature thereof combine to present a recording surface which cannot dig into the surface of the sheet. The stylus assembly indicated in Figure 2 is normally biased by any suitable means towards the surface of the recording sheet 41 as indicated by arrow head 57.

Obviously since it is desired to have the exposed surface 53 of the metallic element 51 in contact with the recording sheet, the spring bias is adjusted and the stylus assembly positioned so that the axis of metallic element 51 intercepts the axis of rotation of the drum 31.

Another advantage which is a direct result of my novel combination of needle type stylus and insulating embedment is that the recording sheet when moving under the conductive face 53 of the stylus 51 is first smoothed down by the insulating surface 54 to effectively eliminate the nap of the recording sheet.

This therefore smoothes the papers in a manner which precludes the deposition of particles upon the conductive stylus 53.

In Figure 3 there is shown a complete stylus assembly utilizing the general principles illustrated in Figure 2 for precluding the accumulation of conductive substances upon the surface of the recording stylus and for utilizing an extremely fine conductive stylus.

As illustrated, the stylus 61 is embedded in an

insulating compound 62. The stylus has an exposed surface 63 similar to that illustrated in Figure 2 and the insulator 62 has a coextensive curved surface 64. In the fabrication of the stylus assembly illustrated in Figure 3 or that illustrated in Figure 2, the insulating material is molded directly about the stylus in any suitable manner. Thus, if the insulating material is a plastic, the normal type of thermal molding may be applied or the stylus 61 may be embedded in molten glass or the like. The stylus is preferably distorted along its length as indicated at 61' in order that when molded within the insulating material, motion thereof and subsequent loosening will be impossible. However, a straight section of the stylus is retained immediately in the vicinity of the exposed area 63.

When the molding process is complete, the surface 63 of the metallic element 61 and 64 of the insulating element 62 are ground or otherwise finished into a smooth continuous surface having a comparatively large radius of curvature.

This may be accomplished by ordinary grinding and polishing materials or is preferably accomplished in the manner which is well known for imparting highly polished spherical surfaces to glass as in lenses. The grinding apparatus is arranged in a predetermined manner so that the end of the metallic element 61 is normal to the surface 64 of the insulating material.

Subsequent to the grinding and polishing operation the insulating material 62 is turned into cylindrical form and the shoulder 65 is formed therein. The stylus support as illustrated in Figure 3 comprises essentially a hollow cylindrical metallic member 66 which slidably supports the insulating material 62 along the cylindrical surface 67 and has the reentrant circular flange 68 for permitting the passage of the smaller diameter section of the insulating material. The reentrant flange 68 is adapted to engage the shoulder 65 to preclude the movement of the stylus beyond predetermined limits.

A second hollow cylindrical or similarly formed metallic member 71 is tapped at 72 to engage corresponding threads upon the outer surface of the cylindrical member 66. A shoulder 73 in the cylindrical member 66 predetermines the depth to which the member 66 will enter the member 71. Prior to the insertion of the cylindrical member 66 carrying the stylus insulating member 62 into the cylindrical member 71, a "pigtail" lead 75 is soldered or otherwise fastened at 76 to an extension 77 of the metallic element 61 of the stylus assembly.

This pigtail lead 75 provides a suitable connection for joining the stylus into its associated facsimile circuit. The assembly is then completed as illustrated by inserting compression spring 81 into the cylindrical member 71 so that the spring bears against the reentrant flange 82 thereof.

The "pigtail" lead is then drawn through perforation 83 and the metallic cylindrical member 71 is threaded into its position as illustrated. The "pigtail" lead may then be removably secured to the frame of the stylus assembly by means of the knurled screw 84 which threads into corresponding threaded perforation 85.

Accordingly this places the metallic stylus at the potential of the metallic supporting members. This of course requires that the drum 31 be insulatedly positioned upon the supporting members. If, on the other hand, it is desired to have the drum at the potential of the supporting

members, the stylus assembly may be insulatedly positioned thereupon.

The compression spring 81 provides a bias on the stylus assembly 61-62 which drives it towards the recording sheet 41 supported upon conductive recording drum 31 in a manner illustrated in Figures 1 and 3.

The outer cylindrical member 71 of the stylus assembly is supported upon a member 87. Thus, a plurality of screws 91, as illustrated in Figure 1, secure the stylus assembly to the bifurcated end 92 of the member 87.

The lower end of the member 87 carries the half nut 36, which when engaged with the rotating feed screw 35 causes the lateral displacement of the entire stylus assembly.

The member 87 is pivotally and slidably positioned upon a fixed rod 93, and is normally biased in any convenient manner so that the stylus assembly tends to contact the record sheet. The inward movement of the stylus holding arrangement is limited by the engagement of the half nut 36 and the feed screw 35 and by the engagement of a roller 94 and a fixed guide rail 95. The roller 94 is carried upon the member 87 by a suitable yoke 96.

As illustrated in Figure 3, the engagement of the roller 94 and the rail 95 is prearranged so that the axis of the straight end of the stylus 61 intersects the axis of the drum.

When it is desired to reset the stylus to a particular position the member 87 is rotated about the rod 93 against its normal bias so that the half nut 36 is disengaged. The stylus carrying member 87 may then be placed in any position, and the half nut reengaged as shown in Figure 1.

When in the operative position as illustrated in Figures 1 and 3, there is considerable clearance at 86 between the shoulder 65 and the flange 68. This clearance at 86 permits the spring 81 to determine the position of the stylus 61-62 against the record sheet.

Further, the spring loading of the stylus as illustrated in Figure 3 permits the stylus to ride easily over the overlap 42 in the paper sheet as illustrated in Figure 3, without in any way injuring the recording sheet or the stylus assembly.

The stylus assembly illustrated in Figure 3 provides extreme flexibility of recording and permits the utilization of a stylus of any desired diameter and thus the printing of very fine lines. Furthermore, it precludes the accumulation of conductive material upon the point of the stylus which would normally tend to distort the recorded image. In the fabrication of the unitary structure of metallic element 61 and insulating member 62, the curvature of the integral surfaces 63 and 64 is predetermined to meet the characteristics of the drum diameter and the particular type of recording sheet utilized.

The insulating material 62 utilized in constructing the stylus assembly indicated must be able to withstand the heating effects of the passage of electrical currents through the stylus member 61 and must be able to withstand the constant wear imposed thereupon during the sliding surface engagement with the record sheet.

It is thus preferable to utilize a material for the insulating member 62 which will wear mechanically at substantially the same rate as the metallic element 61 under the abrasive influence of the recording sheet.

However, due to the simplicity of the particular stylus structure which I have illustrated in Figure 3, it is obvious that the stylus assembly

61—62 may be disassembled as often as required and the surfaces 63—64 thereof re-polished to the necessary curvature. The clearance provided at 86 will permit the spring 81 to maintain the necessary contact pressure between the stylus surface and the record sheet even though the stylus may be shortened slightly during the polishing. Furthermore the straight end of the stylus 61 will permit numerous repolishings without the displacement of the point of contact with the record sheet.

It will now be evident that these specific disclosures may be modified by those skilled in the art, and thus I prefer to be bound by the scope of the appended claims.

I claim:

1. In a facsimile recorder, a member for carrying a sheet on which a record is to be made, a body of insulating material, a stylus comprising a needle-like conductive element of substantially uniform cross-section throughout its length rigidly embedded in said insulating material against movement with respect to said insulating material, one end of said stylus being exposed through one end surface of said insulating material, said one end of said insulating material having a convex curvature of relatively large radius compared to the size of said needle-like stylus, the exposed end being flush with said end surface of said insulating material, said exposed end of the stylus forming with said insulating material a continuous uniform smooth contacting surface, a housing for said body of insulating material and a spring for biasing said body of insulating material into firm contact with said sheet, said stylus being normal to said sheet at the point of contact therewith, a pivoted arm for supporting said housing, and means for predetermined the position of said pivoted arm.

2. In a facsimile recorder, a member for carrying a sheet on which a record is to be made, a

body of insulating material, a stylus comprising a needle-like conductive element of substantially uniform cross-section throughout its length rigidly embedded in said insulating material 5 against movement with respect to said insulating material, one end of said stylus being exposed through one end surface of said insulating material, the portion of said stylus near the exposed end being straight and the remaining portion 10 being distorted along its length, said one end of said insulating material having a convex curvature of relatively large radius compared to the size of said needle-like stylus, the exposed end being flush with said end surface of said insulating material, said exposed end of the stylus 15 forming with said insulating material a continuous uniform smooth contacting surface, a housing for said body of insulating material and a spring for biasing said body of insulating material into firm contact with said sheet, said stylus being normal to said sheet at the point of contact therewith, a pivoted arm for supporting said housing, and means for predetermined the position of said pivoted arm.
